KNOCKDOWN TOY

Henry Greenberg, New York, and John J. O'Connell, Jamaica, N. Y., assignors to Norwalk Lock Company, South Norwalk, Conn., a corporation of Connecticut

Application January 11, 1946, Serial No. 640,435

23 Claims. (Cl. 46—29)

1

The present invention deals with knockdown structural toys and specifically is concerned with new and improved educational toys particularly applicable for convenient assembly of miniature structures to simulate certain types of buildings, bridges, chassis, hoists or parts thereof although in the broadest aspect the invention is not limited in this respect. One object of the invention resides in the provision of an improved knockdown toy wherein a connector embodying complementary and separable clamping members is utilized to swingably or rotatably sustain a plurality of rod holders in the form of expandible and contractible nipples. Another object of the invention is realized in the provision of an improved nipple comprising self retractile separable sections for removably sustaining a brace or rod. Another object is to yieldingly retain the complementary sections of a nipple together by an interrupted but resilient ring permitting slight separation of the sections or the expansion of the nipple on the insertion of a rod or brace into the latter. A further object is to provide a serviceable nipple comprising complementary sections having arcuate arranged slots adapted to receive or interlock with arcuate track means of spaced and adjustably controlled clamping members whereby the nipples in the unclamping relation of the members may be displaced arcuately to predetermined positions and thereafter readily clamped in such predetermined positions. Other objects, advantages and functional and structural features of the invention will be apparent from the following detailed specification taken with the accompanying drawing wherein:

Fig. 1 is a fragmentary part of a demountable toy removably held together by connectors according to one embodiment of the invention.

Fig. 2 is a sectional view on the line 2—2 of Fig. 1.

Fig. 3 is a view similar to Fig. 2 however with the nipples, spring and clamping means removed from the connector.

Fig. 4 is an elevational view of an expandible and contractible rod holding nipple.

Fig. 5 is a plan view of Fig. 4.

Fig. 6 is a view similar to Fig. 4 illustrating a rod yieldingly clamped between complementary separable sections of a nipple.

Fig. 7 is a side view of Fig. 4.

Fig. 8 is an exploded and perspective view of Fig. 6.

Fig. 9 is an exploded view of the support or connector for firmly clamping the complementary sections of the nipples against the rods.

2

Fig. 10 is a perspective view of one connector or nipple support illustrating the manner in which the rod holding nipples may be rotated or swung on the spaced disc of the support in an unclamped relation of the latter, and

Fig. 11 is a view similar to Fig. 2 however illustrating another connector for rotatably sustaining the rod holders or nipples.

According to the invention the ends of the cylindrical rods or braces 10 are removably sustained in split substantially cone shaped nipples or holders N each defined by opposing but identical complementary separable and mating sections 11 and 12 having inner flat faces 13 each interrupted by a semi-circular groove 14 characterizing a cylindrical bore 15 in the assembled relation of the sections.

As illustrated, the upper cylindrical end or head of each assembled nipple N is cylindrical and embodies an annular groove 16 in which the interrupted resilient wire ring 17 is appropriately retained for holding the inside flat faces 13 of the complementary sections 11 and 12 yieldingly together when no rod or brace means 10 is inserted into the bore 15 (Figs. 4 and 5).

With the wire ring 17 yieldingly holding the complementary sections 11 and 12 together, the latter may be separated or expanded slightly on insertion of a rod or brace 10 into the companion semi-circular grooves 14. The reactive force imparted by the interrupted annular wire but resilient ring 17 causes walls of the grooves 14 to engage the rod, thus initially and slightly clamping the latter and even in such clamped relation the retaining ring 17 precludes complete detachment of the complementary clamping sections 11 and 12.

Each of the complementary sections 11 and 12 of a nipple or holder N also embodies an arcuate slot 18 adapted to receive the curved or annular track, flange or rim 19 of a connector or coupling generally denoted C comprising companion nipple sustaining detachably associated discs 20 each including the inwardly disposed complementary hub sections or bosses 21 each having a semi-circular groove 22. Each of the complementary hub sections or guide means 21 also includes a flat face 23 adapted to disengageably contact in the assembled relation of the discs 20 whereupon the grooves 22 are in alignment to form a cylindrical guide bore for the reception of a shank 24 of a screw or bolt 25 adapted to be removably received in the openings 26 in the discs 20 which are held together against separation by a clamping nut 27 mounted on the threaded shank 24.

which in part is surrounded by a helicoidal spring 28 disposed underneath the slotted head 29 of the screw or bolt 25 in the mating cutaway portions 30 and 31 defining the circular recess generally indicated 32. The openings 26 may be said to be the mouths for the bore formed by the semi-circular grooves 22 and for the circular recess 32. By reason of the openings 26, the discs or members 20 may be said for purposes of specification to be annular.

By unloosening the clamping member or nut 27 the companion discs 20 may be moved apart slightly against the resistance offered by the helicoidal spring 28. Hence the nipples or rod holders N may be inserted between the discs so that the curved tracks or flanges 19 readily snap into the arcuate slots 18 of the complementary sections 11 and 12, these slots having an axis or loci of curvature normal to the axis of the nipple N. Or in other words each nipple is interlocked with the companion discs 20 which by reason of the tracks 19 fitting into the arcuate guide slots 18 permit the nipples to be swiveled or rotatably displaced along the tracks 19, that is about the origin of the companion discs 20 to a desired position after which nut 27 is again tightened. By such action the complementary sections 11 and 12 of each nipple firmly clamp against a rod or brace 10.

With the arrangement described, a nipple may be readily mounted between the companion discs 20 or may be conveniently removed therefrom. Even though mounted between these discs a nipple may be retained by the tracks 19 to permit displacement thereof along the curved tracks. However each nipple separates slightly upon insertion of a rod or brace 10 therein against the resistance of the retaining spring ring 17. Should the rod be removed from a nipple, the spring ring 18 immediately contracts and closes the complementary sections 11 and 12 to bring their flat faces 13 again together or in juxtaposition. The grooves 18 of these sections form reduced neck portions 33 merged with the upper semi-circular portions 34 defining the circular head of a nipple and the semi-circular conical portions 35 defining the substantially frusto-conical portions of the nipple.

The retaining ring 17 as previously stated yieldingly holds the complementary sections of a nipple together and thereby permits convenient handling thereof as a unit and as such may be quickly assembled with or attached to the support or connector therefor characterized by the spaced discs 20.

In the embodiment according to Fig. 11, the spring 28 is disposed in a recess 40 in the boss 41 in one of the discs 20 both of which embody the aligned openings 26 for receiving and guiding shank 24 of the bolt 25. In Fig. 2 the bosses or hubs 21 extend appreciably beyond the discs and are separable whereas in Fig. 11 the bosses 41 are not split nor do they extend appreciably beyond their respective annular rims 19. In other aspects the form according to Fig. 11 is along the lines illustrated in Figs. 1-10.

By the present invention the frame work broadly designated F (Fig. 1) for a structural toy may be readily built up or put together. No special skill is required. Since the parts are removably associated the frame work may be readily disconnected whereby the parts may occupy a relatively small space. The type of frame work shown in Fig. 1 is merely illustrative and obviously many other types of structures may be put

together with the herein connector C and rod holders N.

The spring 28 in all of the embodiments disclosed also serves to retract discs 20 against the rod holders N after the latter are inserted between the discs of the connector C.

In Fig. 1 six rod holders N are removably mounted on each connector C. Of course more than six or less than six may be mounted thereon as is well understood, and if desired only one rod and holder may be so mounted. At any rate, each connector C is adapted to removably clamp a plurality of rod supports or holders N.

Various changes may be made in details of construction and arrangement of parts without departing from the spirit of the invention or sacrificing any of the advantages thereof inherent therein.

We claim:

1. In a knockdown toy, brace means, a nipple comprising complementary sections defining a bore for removable reception of said brace means, each of said sections embodying an arcuate slot, spaced members having arcuate track means removably projecting into said slots for guiding displacement of said nipple about said members, and means for clamping said track means against said sections for clamping the latter against said brace means.

2. In a knockdown toy, brace means, a nipple comprising complementary sections defining a bore for removable reception of said brace means, each of said sections embodying an arcuate slot, means for yieldably retaining said sections together, spaced members having arcuate track means removably projecting into said slots for guiding arcuate displacement of said nipple about said members, and means for clamping said track means against said sections for clamping the latter against said brace means.

3. In a knockdown toy, brace means, a nipple comprising complementary sections defining a bore for removable reception of said brace means each of said sections embodying an arcuate slot and a groove spaced from said slot, an interrupted ring confined in said groove for yieldingly retaining said sections together, spaced members having arcuate track means removably projecting into said slots for guiding arcuate displacement of said nipple about said members, and means carried by said members for adjusting the latter to removably clamp said track means.

4. In a knockdown toy, brace means, a nipple comprising complementary sections defining a bore for removable reception of said brace means and each of said sections embodying an arcuate slot, spaced discs having annular track means removably projecting into said slots for guiding arcuate displacement of said nipple about said discs, and means for removably clamping said track means against said sections for removably clamping the latter against said brace means.

5. In a knockdown toy, brace means, a nipple comprising complementary sections defining a bore for removable reception of said brace means and each of said sections embodying an arcuate slot, spaced annular discs having arcuate track means removably projecting into said slots for guiding arcuate displacement of said nipple about said discs, and a bolt and nut carried by said discs for clamping said track means against said sections for clamping the latter against said brace means.

6. In a knockdown toy, brace means, a nipple comprising complementary sections defining a

bore for removable reception of said brace and each of said sections embodying an arcuate slot, spaced means having arcuate track means removably projecting into said slots for guiding arcuate displacement of said nipple about said spaced means, a bolt projecting through said spaced means, and a nut removably mounted on said bolt for moving said spaced means together for removably clamping said track means against said sections for clamping the latter against said brace means.

7. In a knockdown toy, brace means, a nipple comprising complementary sections defining a bore for removable reception of said brace means and each of said sections embodying an arcuate slot, spaced members having arcuate track means removably projecting into said slots for guiding arcuate displacement of said nipple about said members and having aligned guide means, a bolt having a shank removably disposed in said guide means and having a threaded portion, and a nut mounted on said threaded portion for clamping said track means against said sections and the latter against said brace means.

8. In a knockdown toy, brace means, a nipple comprising complementary sections defining a bore for removable reception of said brace means and each of said sections embodying an arcuate slot, spaced discs having arcuate track means removably projecting into said slots for guiding arcuate displacement of said nipple about said discs and having aligned guide means, a bolt having a head and a shank extending from said head and removably receivable in said guide means and including a threaded portion, an internally threaded nut mounted on said threaded portion, and a spring interposed between said head and one of said discs for resisting the separation of the latter.

9. In a knockdown toy, brace means, a nipple comprising complementary sections defining a bore for removable reception of said brace means and each of said sections embodying an arcuate slot, spaced annular discs having arcuate track means removably projecting into said slots for guiding arcuate displacement of said nipple about said discs and having aligned openings and including recessed means in alignment with said openings, a bolt having a head and a shank extending from said head and removably receivable in said openings and including a threaded portion, an internally threaded nut mounted on said threaded portion, and a helicoidal spring surrounding said shank and disposed in said recessed means and cooperating with said head to resist separation of said discs.

10. In a knockdown toy, brace means, a nipple comprising complementary separable sections defining a bore for removable reception of said brace means and each of said sections embodying an arcuate slot, spaced members having arcuate track means extending from said members and removably projecting into said slots for guiding arcuate displacement of said nipple about said members, bosses extending from said members and including guide means, a bolt having a head and including a shank slidably disposed in said guide means and embodying a threaded portion, and an internally threaded nut mounted on said threaded portion for removably clamping said track means against said sections to removably clamp the latter against said brace means.

11. In a knockdown toy, a plurality of brace means, a plurality of nipples each comprising complementary separable sections defining a bore

for removable reception of said brace means and each of said sections embodying an arcuate slot, spaced members removably straddling said nipples and having guide means, arcuate track means extending from said members and removably projecting into said slots for guiding arcuate displacement of said nipple relative to said members, a bolt having a head and including a shank slidably and removably disposed in said guide means and including a threaded portion, and an internally threaded nut mounted on said threaded portion for removably clamping said members against said nipples and for removably clamping said sections against said plurality of brace means.

12. In a knockdown toy, brace means, a nipple comprising separable complementary and tapered sections defining a bore for removable reception of said brace means and each of said sections embodying an exterior arcuate slot, spaced members having arcuate track means removably projecting into said slots for guiding arcuate displacement of said nipple relative to said members, and means carried by said members for adjustably clamping said track means against said sections for adjustably clamping the latter against said brace means.

13. In a knockdown toy, brace means, a nipple comprising complementary separable sections defining a bore for removable reception of said brace means and each of said sections embodying an arcuate slot, spaced members straddling said nipple and having arcuate track means removably projecting into said slots for guiding arcuate displacement of said nipple relative to said members, bosses extending from said members and beyond said track means and including guide means, a bolt having a head and including a shank removably disposed in said guide means and embodying a threaded portion, and an internally threaded nut mounted on said threaded portion for clamping said track means against said sections and the latter against said brace means.

14. In a knockdown toy, brace means, a nipple comprising complementary and separable sections defining a bore for removable reception of said brace means and each of said sections embodying an exteriorly arranged arcuate slot, spaced annular discs removably straddling said nipple and having arcuate track means removably projecting into said slots for guiding arcuate displacement of said nipple relative to said discs, and adjustable means for actuating said discs for clamping said track means against said sections and the latter against said brace means.

15. In a device for sustaining a rod, a split nipple comprising complementary sections having separable and contiguous internally disposed faces and complementary grooves interrupting said faces and defining a bore for removably receiving said rod, said sections embodying complementary head portions and having arcuate slots disposed below said head portions, spaced members removably straddling said sections and having arcuate means removably extending into said slots for movably guiding displacement of said nipple relative to said members, and means for removably clamping said arcuate means against said sections for removably clamping the latter against said rod.

16. In a device for sustaining a rod, a split nipple comprising complementary sections having separable and contiguous internally disposed faces and complementary grooves interrupting said

faces and defining a bore for removably receiving said rod, said sections embodying complementary head portions and having arcuate slots disposed below said head portions, spaced members removably straddling said sections and having arcuate means removably extending into said slots for removably guiding displacement of said nipple relative to said members, spring means closely embracing and surrounding said head portions for yieldingly retaining said sections together, and means for removably clamping said arcuate means against said sections for removably clamping the latter against said rod.

17. A split nipple for receiving a member comprising complementary sections having separable and contiguous internally disposed faces and complementary grooves interrupting said faces and defining a bore for removably receiving said member, said sections embodying complementary head portions and having arcuate slots disposed below said head portions, the axes of the curvature of said slots being normal to the axis of said nipple, and split spring means closely surrounding said nipple for yieldingly retaining said sections against said member.

18. A split nipple for receiving a member comprising complementary sections having separable and contiguous internally disposed faces and complementary grooves interrupting said faces and defining a bore adapted to removably receive said member, said sections embodying complementary head portions and having arcuate slots disposed below said head portions, the axes of the curvature of said slots being normal to the axis of said nipple, and an annular interrupted spring surrounding and embracing said head portions for yieldingly retaining said sections together.

19. In a device for sustaining a rod, a split nipple comprising complementary sections having separable and contiguous internally disposed faces and complementary grooves interrupting said faces and defining a bore for removably receiving said rod, spaced members removably straddling said sections, said members and sections having disengageable interlocking arcuate means for movably guiding arcuate displacement of said nipple relative to said members, and means for removably clamping said members against said sections for removably clamping the latter against said rod.

20. In a device for sustaining a rod, a split nipple comprising complementary sections having separable and contiguous internally disposed faces and complementary grooves interrupting said faces and defining a bore for removably receiving said rod, spaced members removably strad-

dling said sections, said members and sections having disengageable interlocking arcuate means for movably guiding arcuate displacement of said nipple relative to said members, spring means closely embracing and surrounding said sections for yieldingly retaining said sections together, and means for removably clamping said members against said sections for removably clamping the latter against said rod.

10 21. In a knockdown toy, brace means, a nipple comprising companion sections adapted to be spread apart and having complementary grooves defining a bore for removable reception of said brace means and each of said sections embodying slot means disposed in a path through which an arc passes, spaced members straddling said sections and having arcuate track means removably projecting into said slot means for controlling arcuate displacement of said nipple relative to said members, said members each having guide means, a bolt having a head and including a shank removably disposed in said guide means and embodying a threaded portion, and an internally threaded nut mounted on said threaded portion for removably clamping said track means against said sections and the latter against said brace means.

22. In a knockdown toy, brace means, a nipple having head means and comprising complementary sections adapted to be spread apart and defining a bore for removable reception of said brace means and each of said sections embodying slot means disposed in a path through which an arc passes and disposed below said head means, spaced members straddling said sections and having arcuate track means removably projecting into said slot means for controlling arcuate displacement of said nipple relative to said members, said members each having guide means, a bolt having a head and including a shank removably disposed in said guide means and embodying a threaded portion, and an internally threaded nut mounted on said threaded portion for clamping said track means against said sections to clamp the latter against said brace means.

23. A nipple for receiving a brace member comprising juxtaposed sections adapted to be spread apart and having contiguous internally disposed faces and complementary internally disposed grooves interrupting said faces and defining a bore adapted to removably receive said member, and each of said sections having exterior slot means disposed in a path through which an arc passes and having an axis substantially normal to the axis of said bore.

HENRY GREENBERG.
JOHN J. O'CONNELL.
